UNITED STATES PATENT OFFICE

CARL C. HARRIS, OF ORANGE, MASSACHUSETTS

CUP FOR SPONGE MOISTENERS

Application filed October 1, 1928. Serial No. 309,464.

This invention relates to a cup or receptacle for receiving a sponge for use in moistening the fingers for applying moisture to stamps, gummed strips and the like and for other uses.

The principal objects of the invention are to provide a cup or holder for this purpose having means whereby the surplus moisture can be removed from the fingers by drawing the fingers over the sponge and over the edge of the cup, which is so located that it can be done in a single motion in a substantially straight line; to provide means whereby the surplus moisture is drained back into the cup; to provide the cup with simple means serving as a hand grip so that the whole device can be moved about conveniently and to provide the base with means for preventing or retarding the sliding of the article on the surface on which it is located and of such a nature as not to mar such a surface. Some features of this invention are adapted to be used in a stamp pad holder in a similar way.

Other objects and advantages of the invention will appear hereinafter.

Reference is to be had to the accompanying drawings in which

Fig. 1 is a side view of a sponge cup with a sponge therein showing a preferred embodiment of this invention;

Fig. 2 is a sectional view diametrically across the center of the same, and

Fig. 3 is a bottom plan view.

Cups for holding sponges or pads for the purpose of moistening the fingers ordinarily are made in a very simple manner and they are apt to slide around the desk inconveniently and are hard to keep clean. When the fingers are moistened on the sponge, they are apt to receive surplus moisture which will drip on the desk. Furthermore these moisteners are not conveniently portable.

I provide a cup of semi-soft rubber, somewhat flexible, but not very soft, which has a recess 11 in the top for receiving the sponge 12 which may be of sponge rubber. It is shown as circular in form and convex on top. At the bottom of this recess there are two

hold the sponge rubber above the bottom of the recess.

At the top of the recess there is a slanting or curved surface 14 ending in a lip 15 surrounding the cup and having a comparatively sharp circular edge projecting outwardly. Below this is an annular groove 18 surrounding the cup and serving as a handle, the lip projecting above it for this purpose. At the bottom, the base flares out to provide a wide bottom surface for resting on the desk and the bottom of this surface is provided with a series of projections 19 integral with the base for preventing or retarding any sliding of the article around the desk.

The lip, which has been described, serves to wipe the surplus moisture from the bottom surfaces of the fingers of the user if she draws her fingers over the sponge in the natural way and across this lip in a single motion substantially in a straight line. On account of the slanting top surface of the lip, it will cause the surplus water to drain back into the cup. It also serves as the top of the annular groove, enabling the user to grasp the whole device conveniently and transport it from one place to another.

Integral rubber spurs 20 project into the sponge to prevent its accidental displacement.

This constitutes a simple, attractive and convenient article for the purpose described and efficiently serves all the above mentioned purposes. The projections on the bottom and the annular groove can be used in a cup for an ink pad also.

Although I have illustrated and described one form and two applications of the invention I am aware of the fact that other modifications can be made therein by any person skilled in the art without departing from the scope of the invention as expressed in the claims.

Therefore, I do not wish to be limited in this respect but what I do claim is:—

1. As an article of manufacture, a sponge cup moistener comprising a base having a recess in the top, a moistening sponge in said recess having a convex upper surface, the base being provided with an outwardly and upwardly projecting ledge around the top for

receiving the fingers of the operator when
brushed along the surface of the sponge and
removing excess moisture therefrom, said lip
having on the inside a gentle curve so that
the water will drain back into the cup and
the base having a groove entirely around it
underneath and extending to the edge of said
lip whereby it can be lifted and moved
around.

2. As an article of manufacture, a holder
for the purpose described comprising an in-
tegral body of semi-soft rubber having a cav-
ity therein for a moistening element or pad
and provided with a circumferential groove
15 concave in cross section around the surface
just under the top for use in manipulating
the holder and terminating at the top in a
surrounding edge projecting outwardly at
the top of said groove and inclined inwardly
20 and downwardly from its extreme outer edge.

In testimony whereof I have hereunto af-
fixed my signature.

CARL C. HARRIS.
